LEOPOLD LOEBENBERG, OF RIO DE JANEIRO, BRAZIL.

APPARATUS FOR TUBULAR TRANSFERRING SYSTEMS.

1,112,304.

Specification of Letters Patent. Patented Sept. 29, 1914.

Application filed July 22, 1914. Serial No. 852,526.

To all whom it may concern:

Be it known that I, LEOPOLD LOEBENBERG, mechanical engineer, a subject of the King of Prussia, and residing at 60 Rua da Alfândega, Rio de Janeiro, Brazil, have invented certain new and useful Improvements in Apparatus for Tubular Transferring Systems, of which the following is a specification.

10 This invention relates to apparatus adaptable for use as a sender, receiver, or as a passage apparatus (intermediate station) for tubular transferring systems. The apparatus is characterized particularly by extremely great simplicity of the arrangement and manipulation, and consists essentially of a rotary gate, or valve device by the rotation of which the system is tightly closed from the atmosphere and the introduction 15 and removal of the cylinders or boxes is still made possible.

Two examples of construction of the apparatus are illustrated in the accompanying drawings, in which—

25 Figure 1 is a vertical section through one type of apparatus. Fig. 2 is a vertical section at right angles of Fig. 1, in which the gate is closed from the communicating pipe. Fig. 3 shows the gate 30 in a position open to the communicating pipe with a box admitted. The illustrated apparatus shows a receiving device or intermediate station, but it can be applied conversely and with suitable alteration as 35 a sending apparatus, and Fig. 4 is a vertical section through the middle of the apparatus according to another form of construction with valve device closed, and Fig. 40 5 is a section similar to Fig. 4 but the valve device in the discharging position.

Referring to the drawings the gate consists of a rotary drum 1, in which a chamber 2 is formed which serves for the reception of the box or cylinder 3. The chamber 25 of the drum is closed at one end and open at the other. The drum is arranged inside a completely inclosed casing 4 kept under pressure or under vacuum, to which casing at the top and below, the tubes for bringing in and discharging the box, are connected. The joint for keeping the gate drum 1 tight from the atmosphere is made inside the casing 4 by a shoe 5 lying tightly upon the outside surface of the drum, and 50 itself is tightly connected to the pipe passing through the bottom of the casing. The

flange and the wall of the drum are ground into one another or otherwise made with a tight joint. In order to be able to press the flange against the drum it is connected to a tubular piece 7 and to a flange 9 tightened by nuts. By tightening up the nuts 8 the flange 5 can at any time be pressed against the drum 1. For this purpose the tubular piece 7 forms an adjustable joint in 65 a stuffing box 9'.

In the position illustrated in Fig. 1, the gate chamber 2 is shut off from the interior of the casing 4 by the bottom of this chamber, which is now at the top, but it is in 70 connection with the pipe and the receiving outlet 6. If, now a box passes in through the pipe 10 and falls into the receiving pipe 11 thereunder, which can be indicated through inspection openings 12 the drum 1 75 is turned in the direction of the arrow 14 through an angle of 180 degrees by means of the crank handle 13 connected to it, until it takes up the position shown in Fig. 3, so that the box 3 can fall into the gate 80 chamber 2. If, now the gate is again turned back to the position according to Fig. 1 by means of the handle, then the box 3 falls out below, as Fig. 4 shows, and can in this way be removed if the lower pipe 6 is 85 opened. If, now, several boxes are passed one upon the other, an apparatus is provided in order to allow always only one box to pass the gate, since this is suitably designed of such a size only to take one box. 90 For this purpose a double-armed lever 15 is mounted in the casing 4 and the nose 16 of this lever can under the operation of a spring 17 engage through an opening in the side of the receiving pipe 11. A projection or stop 18, arranged on the gate drum 1 beyond the reach of the flange 5, operates in the position shown in Fig. 1 an extension of the lever 15 in such a manner that the nose 16 remains outside the receiving pipe 11. In this position of the lever 15 the boxes can pass the openings into which the nose can pass into the pipe, but now, if the drum 1 is turned through an angle of 180 degrees into the position shown 100 in Fig. 3, this nose engages from the side into the receiving pipe 11 and retains the second box 3' which lies above the lowermost box 3 (see Figs. 2 and 3) so that only the lowermost box 3 can fall into the gate chamber 2, which is now open at the top. If, now, the drum is turned back into the po- 110

sition shown in Figs. 1 and 4, the lever 15 is pushed back at the same time by the stop 18 until the nose 16 passes out of the receiving pipe 11 and the box 3' is free to fall down. In this way it comes about that always only a single box can pass into the gate chamber while the box above this one is held fast.

10 The gate drum 1 can be formed differently. In the construction illustrated by Figs. 1-3 the gate drum is mounted upon a horizontally placed shaft and there is only one chamber which has its opening turned about the horizontal axis to the top 15 or to the bottom.

15 With the form of construction illustrated by Figs. 4 and 5 the section pipe 2^a is fixed in the interior of the rotatable valve 1^a and arranged as a continuation of the receiving pipe. The fixed section pipe 2^a is surrounded by the circular valve 1^a which has a suitable opening for passing through the boxes. The position of this valve in Fig. 4 is to receive the box, whereas the Fig. 5 20 shows the discharging position of the valve, the latter being turned through 180 degrees. The advantage of this construction is, that the box is not turned by its way through the valve but falls out in the same position as 25 arrived.

30 A jointing shoe is pressed against the outer surface of the circular valve similar to the form of construction illustrated by Figs. 1-3.

35 Having now particularly described and ascertained the nature of my said invention, and in what manner the same is to be performed, I declare that what I claim is:

40 1. In a cylinder transferring device, the combination of a casing having pipes leading from its upper and lower ends and forming cylinder passages, a receiving pipe disposed in the casing with its upper open end below the upper casing pipe to receive 45 cylinders therefrom, a rotary transfer drum mounted at the lower end of the receiving pipe and having a diametrical chamber closed at one end and adapted to register with the receiving pipe, and a tubular member below said drum, with which the said drum chamber is also adapted to communicate, communicating at its lower end with the lower casing pipe.

50 2. In a cylinder transferring device, the combination of a casing having pipes leading from its upper and lower ends and forming cylinder passages, a receiving pipe disposed in the casing and with its upper open end below the upper casing pipe to receive 55 several cylinders therefrom in superposed relation, a rotary transfer drum mounted at the lower end of the receiving pipe and having a diametrical chamber closed at one end and adapted to register 60 with the receiving pipe, means to engage

a cylinder in the receiving pipe and prevent the same from dropping into the transfer drum, and a tubular member below said drum, with which said drum chamber is also adapted to communicate, communicating at 70 its lower end with the lower casing pipe.

3. In a cylinder transferring device, the combination of a casing having pipes leading from its upper and lower ends and forming cylinder passages, a receiving pipe disposed in the casing with its upper open end below the upper casing pipe to receive 75 cylinders therefrom, a rotary transfer drum mounted at the lower end of the receiving pipe and having a diametrical chamber closed at one end and adapted to register with the receiving pipe, and a tubular member below said drum, with which the said drum chamber is also adapted to communicate, communicating at its lower end with 80 the lower casing pipe, and a shoe carried by the upper end of said tubular member and snugly engaging the lower portion of the periphery of said drum.

4. In a cylinder transferring device, the combination of a casing having pipes leading from its upper and lower ends and forming cylinder passages, a receiving pipe disposed in the casing with its upper open end below the upper casing pipe to receive 85 cylinders therefrom, a rotary transfer drum mounted at the lower end of the receiving pipe and having a diametrical chamber closed at one end and adapted to register with the receiving pipe, and a tubular member below said drum, with which the said drum chamber is also adapted to communicate, communicating at its lower end with 90 the lower casing pipe, and a shoe carried by the upper end of said tubular member and snugly engaging the lower portion of the periphery of said drum.

95 5. In a cylinder transferring device, the combination of a casing having pipes leading from its upper and lower ends and forming cylinder passages, a receiving pipe disposed in the casing with its upper open end below the upper casing pipe to receive 100 cylinders therefrom, a tubular member below and spaced from the receiving pipe and communicating at its lower end with the lower casing pipe, and a transfer member 105 mounted to move in the space between the said receiving pipe and the said tubular member and adapted to close one while in communication with the other.

110 6. In a cylinder transferring device, the combination of a casing having pipes leading from its upper and lower ends and forming cylinder passages, a receiving pipe disposed in the casing with its upper open end below the upper casing pipe to receive 115

cylinders therefrom, a tubular member below and spaced from the receiving pipe and communicating at its lower end with the lower casing pipe, a transfer member 5 mounted to move in the space between the said receiving pipe and the said tubular member and adapted to close one while in communication with the other, said transferring member consisting of a rotatable 10 cylinder having an aperture through its circular wall at one point, and a vertical

stationary tube within the said cylinder to receive the cylinders to be transferred, whereby the transfer may be effected without reversing the cylinders during transferring, substantially as described. 15

In testimony whereof I have affixed my signature in presence of two witnesses.

L. LOEBENBERG.
